CARRIER FOR CONTAINERS

Julian B. Slevin, Jr., Drexel Hill, Pa.

Application June 17, 1942, Serial No. 447,324

12 Claims. (Cl. 229—52)

This invention relates to carriers for containers such as bottles, cans, or other packages, used for beverages and foods, the carrier preferably being made from a single sheet of card-board, or similar material, suitably blanked and formed so that the same may be shipped to the initial user thereof in folded flat condition ready to be set up for use.

Heretofore, I have devised a form of carrier for containers as described and shown in my previous application for Letters Patent, filed April 24, 1940, Serial No. 331,279, which carrier has become quite popular and has gone into large and extensive use.

The principal object of the present invention is to provide a carrier for containers such as bottles and the like, made from sheet material, preferably a single sheet of cardboard, paper board, or similar tough, flexible material, in which carrier the containers placed therein will be securely held against accidental displacement.

A further object of the invention is to provide a carrier for containers in which a lighter stock may be safely employed that has heretofore been commonly used in the manufacture of such carriers.

A further object of the invention is to provide in a carrier of the character aforesaid, such an arrangement of the parts that the various strains imparted to the structure when in use will be adequately provided for, in that the carrier will be suitably re-inforced at various places where the greatest strains occur, thus permitting the use of a thinner material.

A further object of the invention is to provide a carrier of the character aforesaid, and having the several advantages as above set forth, which can be partially formed, or arranged for setting up, in the machines used for the production of carriers made in the form described and shown in my previous application for Letters Patent, without requiring much change in the construction and arrangement of said machines.

The nature and characteristic features of the present invention will be more readily understood from the following description, taken in connection with the accompanying drawings forming part hereof, in which:

Fig. 1 is a plan view of a blanked sheet from which the carrier is made, the same being shown in flat condition before being formed and set up;

Fig. 2 is a similar view, but showing the blank in a partially folded condition, at an intermediate stage in the formation of the carrier;

Fig. 3 is a similar view of the carrier in a more advanced stage of its formation;

Fig. 4 is a view similar to Fig. 3, with the bottom panels being shown in-folded and the side panels off-set to bring the carrier to the condition in which the same is preferably delivered to the original user thereof;

Fig. 5 is a side elevation of the carrier in the fully set-up condition, ready to receive the bottles or other containers which are to be carried therein;

Fig. 6 is an elevational view of one end of the carrier in the condition as shown in Fig. 5;

Fig. 7 is a similar elevational view of the other end of the carrier in the condition as shown in Fig. 5;

Fig. 8 is an enlarged plan view of the carrier in the set-up and open condition, ready to receive the containers therein; and

Fig. 9 is a vertical central sectional view, enlarged, of the carrier, the section being taken on the line 9—9 of Fig. 8.

It should, of course, be understood that the description and drawings herein are illustrative merely and that various modifications and changes may be made in the structure and arrangement disclosed without departing from the spirit of the invention.

Referring to the drawings, and now more particularly to Fig. 1 thereof, the sheet or blank, from which the carrier is made, preferably comprises a single sheet of material such as card-board, paper-board, or similar tough flexible material suitably shaped, and provided with crease lines as shown therein and as required to define the various parts.

The blank 10, preferably consists of two main portions, the portion 11 comprising, in the main, the internal parts of the carrier, and the portion 12 comprising, in the main, the external parts of the structure. The portions 11 and 12 are joined to each other along a longitudinal crease line 13.

The portion 11 is provided with two bottom panels 14, connected to each other along a central transverse crease line 15. The bottom panels 14 are respectively joined along a transverse crease line 16 to a portion 17 which constitutes a part of a wall on each side of the container when the same is set up.

Each of the portions 17 is joined, by means of inclined partition members 18 to a panel 19 which provides a part of a centrally disposed partition from which one of the portions 20 of a handle extends. The handle portion 20 is con-

nected to the panel portion 19 along transverse crease lines 25. The inclined partition members 18 are respectively joined along the longitudinal crease lines 21 at one end to the portion 17, and at the other end along similar longitudinal crease lines 22 to the central partition panel 19.

Each of the panels 19, to which the handle elements 20 are connected, is also connected, along a longitudinal crease line 23 to an end wall panel 24 which is joined along the longitudinal crease line 13 to a part of the portion 12, as will be hereinafter more fully set forth.

The outer portion 12 of the carrier is likewise provided with bottom panels 26 joined to each other along a central transverse crease line 27. It should here be noted that in the blank the bottom panels 14 of the portion 11 have their ends abutting adjacent ends of the bottom panels 26 of the portion 12, and that these bottom panels are not united along these end margins, but are separated by a cut line 28 thereby enabling the carrier to be formed and set up without binding at this point.

The bottom panels 26 of the portion 12 are each joined along a transverse crease line 30 to an outer side wall panel 31. Each of the outer side wall panels 31 is connected, along a longitudinal crease line 32, to one end of the outer wall part 17 of the portion 11. The longitudinal crease lines 32 are in effect extensions of, or disposed in alignment with, the longitudinal crease lines 13 which are provided between the panels 24 and 31 on each side of the structure. Each end panel 24 is also joined along the longitudinal crease line 13 to an outer side wall panel 31.

The end panel 24 is also joined along another extension 33 of the longitudinal crease line 13 by means of a part 34 to a panel 36 which in the set up carrier, constitutes a portion of the central vertical partition structure. The part 34 is joined to the panel 36 along a longitudinal crease line 35. Each panel 36 also has an extending handle portion 37 complementary to the extending handle portions 20 of the parts 19 of the central partition structure, being joined thereto along transverse crease lines 48.

Each of the outer side panels 31 of the portion 12 is connected to a panel 38 along a longitudinal crease line 39. Each of said panels 38 has upper and lower inclined edges, and said panels form the end walls of the carrier. The outer side wall panel 31 on each side is separated from the portions 34 and 35 by means of the transverse cut line 40 and likewise each end wall panel 38 is separated from the adjacent central panel 36 by means of an inclined cut line 41.

Joined to the end panels 38 and to the partition panels 36 along longitudinal crease lines 42 are tabs 43 which in the set up structure are in-turned and secured to corners 44 of the panels 19 by means of wire stitching 45 (see Fig. 2). To permit the stitching at this point, a small tab 46 is cut out of each of the end members 38, which tabs 46 are stitched to the main tabs 43 when the same is secured to the corners of the panels 19.

After the carrier has been partly formed, to the condition shown in Fig. 2 of the drawings, the same is then folded along the transversal crease lines 15 and 27 to bring the same to the condition shown in Fig. 3 of the drawings. The parts 36, towards each end of the blank, as well as the parts 19, which are now disposed between the parts 36, are all secured to each other, preferably

by means of the wire stitching 49. (See Figs. 3 and 4.)

The carriers may, if desired, be shipped to the user in the condition as shown in Fig. 3 of the drawings, but preferably they are subjected to another operation to bring the same to the condition as shown in Fig. 4 of the drawings. In this operation the bottom panel members 26 and 14 are inturned to cause the same to be disposed within the structure between the panels 31 and the panels 17. At the same time the outer side walls, including the panels 31 and the panels 17, are shifted sidewise to bring the same to the offset relationship as shown in Fig. 4 of the drawings. When the carriers are subjected to this operation, by reason of the inherent strains thereby impressed upon the various parts, as soon as the carriers are released from their packages they will spring to approximately the full open position, as shown in Figs. 5 to 9 of the drawings, and they will then be ready to have the bottles, or other containers, inserted in the respective compartments provided for the reception thereof.

By the foregoing arrangement there is provided a bottle carrier in which the outer side walls, as well as the end walls extend upwardly a distance sufficient to insure the proper retention of the bottles or other containers, when the same are placed therein, and will preclude the accidental displacement of the bottles or other containers therefrom.

It will be noted that in this, as in the preceding forms of bottle carriers devised by the present inventor, the bottles may be readily placed in the containers, and may be easily removed therefrom, when the containers are in the fully set up condition.

I claim:

1. A carrier for containers such as bottles and the like, made of flexible sheet material and including spaced outer side panels, outer bottom panels connected to the lower edges of said side wall panels along transverse crease lines, central partition sections extending above said side wall panels, end wall panels connected to said outer side wall panels and to said central partition section along crease lines, inner side wall panels, inner bottom panels overlying said outer bottom panels and connected to the lower edges of said inner side wall panels along transverse crease lines, and inclined partition members disposed in vertical planes parallel to the end wall panels and connected to the inner side wall panels and to the central partition sections along crease lines.

2. A carrier for containers such as bottles and the like, made from a single sheet of flexible material and including spaced outer rectangular side panels, outer bottom panels connected to the lower edges of said side wall panels along transverse crease lines, central partition sections extending above said side wall panels, end wall panels connected to said outer side wall panels and said central partition sections along longitudinal crease lines, inner side wall panels, inner bottom panels connected to the lower edges of said inner side wall panels along transverse crease lines, and inclined partition members disposed in vertical planes parallel to the end wall panels and connected to the inner side wall panels and to the central partition sections along longitudinal crease lines.

3. A carrier for containers such as bottles and the like, made from a single sheet of flexible material and including spaced outer rectangular side

panels, an outer bottom panel connected to the lower edges of said side wall panels along transverse crease lines, central partition sections extending above said side wall panels, end wall panels connected to said outer side wall panels and said central partition sections along longitudinal crease lines, inner side wall panels, inner bottom panels connected to the lower edges of said inner side wall panels along transverse crease lines, and inclined partition members disposed in vertical planes parallel to the end wall panels and connected to the inner side wall panels and to the central partition section along longitudinal crease line, and handle portions extending upwardly from the central partition sections.

4. A carrier for containers such as bottles and the like, comprising a sheet of flexible material blanked and creased to provide two principal portions, one portion comprising, in the main, the internal parts, and the other portion comprising, in the main, the external parts of the structure, each of said portions having bottom panels upon which the containers rest in the carrier, the bottom panels of the internal portion being connected along transverse crease lines to parts forming internal sections of the side walls of the structure, the blank also having centrally disposed upper sections, inclined strips joined to said sections along longitudinal crease lines and spacing said upper sections from the bottom panels and from the side wall structure, the external portion of the blank having panels forming the external sections of the side walls of the structure, the blank having panels forming walls at each end of the structure and connected at each longitudinal edge portion to other parts of the structure, and the upper sections having handle extensions.

5. A carrier for containers such as bottles and the like, comprising a sheet of flexible material blanked and creased to provide two principal portions, one portion comprising, in the main, the internal parts, and the other portion comprising, in the main, the external parts of the structure, each of said portions having bottom panels upon which the containers rest in the carrier, the bottom panels of the internal portion being connected along transverse crease lines to parts forming internal sections of the side walls of the structure, said portion of the blank also having centrally disposed upper sections, and inclined strips joined to said sections along longitudinal crease lines spacing said upper sections from the bottom panels and from the side wall structure; the external portion of the blank having panels forming the external sections of the side walls of the structure, said panels being joined to the external bottom panels along transverse crease lines, and panels forming walls at each end of the structure and connected at each longitudinal edge portion to other parts of the structure.

6. A carrier for containers such as bottles and the like, comprising a sheet of flexible material blanked and creased to provide two principal portions, one portion comprising, in the main, the internal parts, and the other portion comprising, in the main, the external parts of the structure, each of said portions having bottom panels upon which the containers rest in the carrier, the bottom panels of the internal portion being connected along transverse crease lines to parts forming internal sections of the side walls of the structure, said portion of the blank also

having centrally disposed upper sections, and inclined strips joined to said sections along longitudinal crease lines spacing said upper sections from the bottom panels and from the side wall structure; the external portion of the blank having panels forming the external sections of the side walls of the structure, said panels being joined to the external bottom panels along transverse crease lines, panels forming walls at each

5 end of the structure and connected at each longitudinal edge portion to other parts of the structure, and the upper sections having handle extensions.

7. A carrier for containers such as bottles and the like, comprising a sheet of flexible material blanked and creased to provide two principal portions, one portion comprising, in the main, the internal parts, and the other portion comprising, in the main, the external parts of the structure, each of said portions having bottom panels upon

20 which the containers rest in the carrier, the bottom panels of the internal portion being connected along transverse crease lines to parts forming internal sections of the side walls of the structure, said portion of the blank also having centrally disposed upper sections, and inclined strips joined to said sections along longitudinal

25 crease lines spacing said upper sections from the bottom panels and from the side wall structure; the external portion of the blank having panels forming the external sections of the side walls of the structure, said panels being joined to the external bottom panels along transverse crease lines, panels forming walls at each end of the

30 structure and connected at each longitudinal edge portion to other parts of the structure, the external portion of the blank also having upper sections, and some of the upper sections having handle extensions.

8. A carrier for containers such as bottles and the like, comprising a sheet of flexible material blanked and creased to provide two principal portions, one portion comprising, in the main, the internal parts, and the other portion comprising, in the main, the external parts of the structure, each of said portions having bottom panels upon

45 which the containers rest in the carrier, the bottom panels of the internal portion being connected along transverse crease lines to parts forming internal sections of the side walls of the structure, said portion of the blank also having centrally disposed upper sections, and inclined strips joined to said sections along longitudinal

50 crease lines spacing said upper sections from the bottom panels and from the side wall structure; the external portion of the blank having panels forming the external sections of the side walls of the structure, said panels being joined to the external bottom panels along transverse crease lines, panels forming walls at each end of the

55 structure and connected at each longitudinal edge portion to other parts of the structure, the external portion of the blank having upper sections superimposed over the upper sections of the internal portion of the blank, and some of said upper sections having handle extensions.

9. A carrier for containers such as bottles and the like, comprising a sheet of flexible material blanked and creased to provide two principal portions, one portion comprising, in the main, the internal parts, and the other portion comprising, in the main, the external parts of the structure, each of said portions having bottom panels upon which the containers rest in the carrier, the bottom panels of the internal portion

being connected along transverse crease lines to parts forming internal sections of the side walls of the structure, said portion of the blank also having centrally disposed upper sections, and inclined strips joined to said sections along longitudinal crease lines spacing said upper sections from the bottom panels and from the side wall structure; the external portion of the blank having panels forming the external sections of the side walls of the structure, said panels being joined to the external bottom panels along transverse crease lines, panels forming walls at each end of the structure and connected to the external sections of the side walls of the structure and also connected to the upper sections of the portion of the blank which forms the internal structure, and the external portion of the blank having upper sections superimposed over the upper sections of the internal portion of the blank, and some of said upper sections having handle extensions.

10. A carrier for containers such as bottles and the like, comprising a sheet of flexible material blanked and creased to provide two principal portions, one portion comprising, in the main, the internal parts, and the other portion comprising, in the main, the external parts of the structure, each of said portions having bottom panels upon which the containers rest in the carrier, the bottom panels of the internal portion being connected along transverse crease lines to parts forming internal sections of the side walls of the structure, said portion of the blank also having centrally disposed upper sections, and inclined strips joined to said sections along longitudinal crease lines spacing said upper sections from the bottom panels and from the side wall structure; the external portion of the blank having panels forming the external sections of the side walls of the structure, said panels being joined to the external bottom panels along transverse crease lines, panels forming walls at each end of the structure and connected along longitudinal crease lines to the external sections of the side walls of the structure and also connected to the upper sections of the portion of the blank which forms the internal structure, and the external portion of the blank having upper sections superimposed over the upper sections of the internal portion of the blank, said upper sections being secured to each other, and some of said upper sections having handle extensions.

11. A carrier for containers such as bottles and the like, comprising a sheet of flexible material blanked and creased to provide two principal portions, one portion comprising, in the main, the internal parts, and the other portion comprising, in the main, the external parts of the structure, each of said portions having bottom panels upon which the containers rest in the carrier, the bottom panels of the internal portion being connected along transverse crease lines to parts forming internal sections of the side walls

of the structure, said portion of the blank also having centrally disposed upper sections, and inclined strips joined to said sections along longitudinal crease lines spacing said upper sections from the bottom panels and from the side wall structure; the external portion of the blank having panels forming the external sections of the side walls of the structure, said panels being joined to the external bottom panels along transverse crease lines, panels forming walls at one end of the structure and connected along longitudinal crease lines to the external sections of the side walls of the structure and to the upper sections of the portion of the blank which forms the internal structure, panels forming walls at the other end of the structure and joined along longitudinal crease lines to the external sections of the side walls of the structure, means for securing the other edges of said panels to portions of said upper sections, and the external portion of the blank having upper sections superimposed over the upper sections of the internal portion of the blank, said upper sections being secured to each other, and some of said upper sections having handle extensions.

12. A carrier for containers such as bottles and the like, comprising a sheet of flexible material blanked and creased to provide two principal portions, one portion comprising, in the main, the internal parts, and the other portion comprising, in the main, the external parts of the structure, each of said portions having bottom panels upon which the containers rest in the carrier, the bottom panels of the internal portion being connected along transverse crease lines to parts forming internal sections of the side walls of the structure, said portion of the blank also having centrally disposed upper sections, and inclined strips joined to said sections along longitudinal crease lines spacing said upper sections from the bottom panels and from the side wall structure; the external portion of the blank having panels forming the external sections of the side walls of the structure, said panels being joined to the external bottom panels along transverse crease lines, panels forming walls at one end of the structure and connected along longitudinal crease lines to the external sections of the side walls of the structure and to the upper sections of the portion of the blank which forms the internal structure, panels forming walls at the other end of the structure and joined along longitudinal crease lines to the external sections of the side walls of the structure, tabs joined to said panels along longitudinal crease lines, said tabs overlapping and being secured to portions of said upper sections, and the external portion of the blank having upper sections superimposed over the upper sections of the internal portion of the blank, said upper sections being secured to each other, and some of said upper sections having handle extensions.

JULIAN B. SLEVIN, JR.
